ABSTRACT OF THE DISCLOSURE

This invention relates to a miniature hand-held boiler heated by a disposable pyrotechnic cartridge that can be connected to an ordinary garden hose. Water can be fed through the hollow handle directly into the boiler in substantial volume to be heated or, alternatively, it can be sprayed therein and converted to steam. The gases evolved from the burning pyrotechnic device are mixed with the steam in the spray nozzle to impart additional energy to the latter. Means are also provided for admitting water from the boiler into the cartridge chamber for the purpose of extinguishing the pyrotechnic device.

Steam-cleaning of an automobile or truck engine to remove dirt, oil and road grime constitutes excellent preventative maintenance; yet, it is a practice that is all too often neglected because of the expense and trouble of having it done. Commercial vehicles, especially large diesel-powered tractor-trailer units, require steam-cleaning at more frequent intervals than the ordinary passenger automobile if they are to operate properly. As a result, the owners of such equipment usually have steam-cleaning equipment in their maintenance shops. In many instances, steam is used to clean the trailer, wheels, chassis and other unpainted surfaces as well as the engine at the end of each trip.

Steam-cleaning equipment is, however, quite expensive and well beyond the price range of most individual truck owners. A large-size commercial unit of the type used by trucking companies will run several thousand dollars while even the small ones found in the neighborhood filling station cost several hundred. As a result, most individual truck owners and some small fleet owners are forced to have their trucks cleaned by a commercial cleaning establishment, usually at a cost of between \$30.00 and \$50.00 per cleaning. Obviously, this is a considerable expense, especially when it has to be done frequently to keep the truck running properly.

There have been a number of hand-held steam-generating devices in the prior art; however, none of them come close to generating sufficient quantities of steam to clean an internal combustion engine. Examples of this type of equipment would be steam irons, vaporizers, facial saunas, etc. Ordinary household electrical current, even 220 volt current, is incapable of generating sufficient wattage to boil the quantity of water required for steam-cleaning an engine. In fact, all such appliances use a water reservoir of some type rather than a flowing supply for the simple reason that household electrical current cannot produce sufficient B.T.U.'s fast enough to continuously vaporize even a small volume flowing stream. Accordingly, one must look to something besides relatively low-voltage electrical current as the source of heat.

Most steam-cleaning units employ gas-fired boilers of some type that make them quite expensive and also prevent them from being portable. They are costly to operate and must be used frequently if they are to pay for themselves.

2

It has now been found in accordance with the teaching of the instant invention that the aforementioned difficulties can be overcome by using as a heat source a simple and inexpensive disposable pyrotechnic cartridge. With the heat source thus solved, the steam-cleaning unit takes on a completely different design than those of the prior art in that it becomes a simple and inexpensive hand-held unit. The instant design includes unique provisions for generating both hot water and steam. Moreover, the gases generated by combustion of the pyrotechnic cartridge are fed back into the stream of hot water or steam so as to substantially eliminate such gases from the atmosphere while, at the same time, utilizing the kinetic energy contained therein as a propellant to impart additional force to the issuing stream of steam or water. A simple garden hose attached to a conventional water tap provides the source of water. If desired, any one of a number of different commercially-available aspirator-type soap or insecticide dispensers can be connected into the system ahead of the steam generator of the present invention to introduce a liquid detergent into the stream issuing from the latter. A simple threaded cartridge-holder allows the cartridge to be backed out of the boiler a short distance so as to admit water to the burning end thereof in order to extinguish same.

It is, therefore, the principal object of the present invention to provide a novel and improved hand-held portable steam-cleaning tool.

A second objective is to provide a device of the type aforementioned that utilizes a simple pyrotechnic cartridge as the source of heat.

Another object of the invention herein disclosed and claimed is to provide a miniaturized steam-cleaning outfit that utilizes the kinetic energy of the combustion gases generated by the burning of a pyrotechnic cartridge to impart additional pressure to the issuing stream of steam or water.

Still another objective is the provision of a miniature steam boiler that includes means for spraying the incoming flow of water into the boiler so as to produce a number of small streams that are more easily vaporized due to their greatly increased surface area and better heat transfer characteristics.

An additional object is to provide a unit of the class described above that includes provision for extinguishing a partially-spent pyrotechnic cartridge by admitting the water in the boiler to the burning end thereof.

A further object is to provide a miniaturized steam-generating apparatus that is simple, inexpensive, easy to use, safe, compact, versatile, rugged and even decorative in appearance.

Other objects will be in part apparent and in part pointed out specifically hereinafter in connection with the description of the drawings that follows, and in which:

FIGURE 1 is a side elevation, considerable portions of which have been broken away and shown in diametrical section, revealing the steam-cleaning apparatus of the instant invention with the nozzle removed;

FIGURE 2 is a section taken along line 2—2 of FIGURE 1, portions of the handle having been broken away to conserve space;

FIGURE 3 is a fragmentary section taken along line 3—3 of FIGURE 1 showing the details of the cartridge-holder and boiler tube designed to house same;

FIGURE 4 is a fragmentary side elevation showing the nozzle in diametrical section with portions of the latter broken away to conserve space; and

FIGURE 5 is a side elevation to a reduced scale showing the entire assembly attached to a garden hose.

Referring now to the drawings for a detailed description of the present invention and, initially, to FIGURE 5 for this purpose, reference numeral 10 has been selected to

designate the entire steam-cleaning device in a general way and numeral 12 the water supply therefor which, in the present instance, is a simple garden hose. The cold tap water enters the boiler 14 through either hollow handle 16 or, alternatively, a bypass tube 18. Valve 20 controls the flow of water through the hollow handle, whereas, a similar valve 22 in the bypass line 18 performs a like function in the latter element. A removable cartridge-holder 24 adapted to receive a pyrotechnic cartridge (not shown) screws into the boiler 14 and, with the cartridge burning, provides the source of heat for the water. The hot water or steam, depending upon the flow rate of the water into the boiler, is discharged along with the gaseous products of combustion through a nozzle 26.

It is oftentimes desirable to introduce a liquid detergent into the emerging stream of hot water or steam to facilitate the removal of road grime, grease, oil, tar and the like that are difficult to cut with water or steam alone. It becomes a simple matter to do so by merely connecting one of the commercially-available aspirator-type soap or insecticide reservoirs found in most hardware stores between the hose and steam-generating unit.

With this general background, reference will now be made to FIGURE 1-4, inclusive, for a more detailed description of the aforementioned components. In the particular form shown, boiler 14 comprises a hollow cylindrical metal cylinder open at the rear end with an internally-threaded ring 28 fastened inside thereof. The front end of the cylinder is capped by a more or less spherically-shaped endpiece 30 that has an integrally-formed externally-threaded tubular neck 32 projecting forward axially from the central opening 34 therein. Front and rear inlet openings 36 and 38 are provided in the cylindrical wall arranged in longitudinally-spaced relation to one another and in position to receive water from the hollow handle 16. It has been found that the small propane cylinders of the type used on soldering torches, camp stoves and the like can be easily modified for use as the boiler 14 of the instant apparatus.

Handle 16 can be fabricated from either metal or, preferably, some type of plastic similar to that from which steam iron handles are made. It is hollow and has a generally inverted U-shaped configuration except for the inlet tube 40 projecting rearwardly therefrom that contains flow-control valve 20. The downturned legs 42 and 44 of the handle register with the openings 36 and 38 that communicate the interior of the boiler and they are provided with external flanges 46 that can be seen most clearly in FIGURE 2 and which enable said handle to be fastened to the boiler wall in fluid-tight sealed engagement by rivets 48. Gaskets 50 are interposed between the flanges and boiler wall for sealing purposes. These gaskets also provide an insulating barrier that prevents much of the heat from the hot boiler wall from being conducted to the handle. Of course, with valve 20 open and cold water flowing through the handle, it remains quite cool to the touch. It is only when the valve 20 is closed and the cold water is bypassed through conduit 18 that any opportunity exists for the handle to heat up. Experience has shown that even with the valve 20 fully-closed, the handle remains cool enough to hold without any discomfort to the user, probably because of the close proximity of the cold tap water in inlet 40 coupled with the fact that most of the steam is generated at the extreme front end of the boiler, it being necessary for the water to progress substantially the full length thereof before sufficient heat is transferred thereto to bring about vaporization. In any event, if handle 16 becomes uncomfortable to hold, it is only necessary to crack valve 20 and bleed a little cold water into it for cooling purposes. The small volume of water needed to cool the handle will not materially affect the ability of the unit to generate steam in the boiler, the heat output of the pyrotechnic device being ample to boil the relatively small volume of water allowed to flow therethrough.

Now, the rear end of the boiler is closed by a plug sub-assembly that has been indicated in a general way by reference numeral 52 and which carries the cartridge-holder 24 as will be explained in detail presently. This subassembly includes an axially-extending tubular member 54 whose inside diameter is slightly greater than the outside diameter of tubular cartridge-holder 24 which fits loosely inside thereof. Tubular member 54 extends forwardly in the boiler to a point substantially coextensive with the front end of the cylindrical portion of the latter in the particular form illustrated. The front end has a disk-shaped plate 56 permanently fastened thereto and a small diameter tube 58 projecting therefrom axially out through and beyond the threaded neck 32 on the front end of the boiler. Tube 58 communicates the interior of tube 54 by means of central opening 60 in disk 56. Abutting the inside surface of disk 56 is an annular high-temperature gasket 62, the function of which will be set forth presently. Immediately behind said gasket lies a series of angularly-spaced apertures 64 through the cylindrical wall of tube 54 which admit water from the boiler into the open front end of the cartridge tube 24 when the latter is backed off of gasket 62.

The rear end of tube 54 extends back well beyond internally-threaded ring 28 at the rear extremity of the boiler. This rearwardly-projecting portion 66 of tube 54 is threaded internally to receive cartridge-holder 24. Obviously, by screwing the tubular cartridge-holder forward until the front end thereof engages gasket 62 and seals thereagainst, water inside boiler 14 passing through apertures 64 in tube 54 is effectively prevented from entering the open front end of the cartridge-holder. It should, perhaps, be mentioned at this point that the gasket 62 need not make a perfect water-tight seal with the end of the cartridge because a small amount of water entering the latter is insufficient to extinguish or even substantially diminish the heat output of a pyrotechnic cartridge of the type used herein, these being quite difficult to put out. This fact has its advantages because gasket 62 must be able to withstand the highest temperatures generated by the burning pyrotechnic cartridge and, if a perfect water-tight seal were necessary, it would be difficult to find a gasket material having sufficient heat resistance. As it is, however, asbestos or even ceramic and metal gaskets can be employed for this purpose. In fact, the gasket could, if desired, be eliminated entirely and have the cartridge tube seal directly against the inside surface of end plate 56 although a simple asbestos gasket would be simpler and easier.

When the time comes to extinguish the pyrotechnic device, the cartridge-holder 24 need only be unscrewed a short distance to open a gap between the front end of the latter element and gasket 62 wide enough to admit water from the boiler in sufficient quantities to douse the flame. The usual pyrotechnic device of a type suited for use in the instant steam-generating apparatus will probably require a minute or so to extinguish and it is best to open at least valve 20 and preferably both valves 20 and 22 when attempting to do so, the flow through conduit 18 alone being so small as to require an undue length of time.

Surrounding rearwardly-extending projection 6 of tube 54 is an annular chamber 68 into which the bypass conduit 18 is connected. This chamber is defined by cylindrical wall 70 (FIGURE 1) that forms a continuation of the cylindrical boiler wall, a solid endplate 72 that interconnects tubular extension 66 and wall 70, a perforated endplate 74 containing apertures 75 extends outward radially from tube 54 at its juncture with extension 66 to the inner threaded surface of ring 28, a solid inwardly-extending radial flange 76 adapted to abut the rear face of ring 28, and an externally-threaded cylindrical section 78 bridging the space between elements 74 and 76 that screws into ring 28. Perforated plate 74 together with threaded section 78 and radial flange 76 cooperate to produce an off-

set endwall in the front end of chamber 68 that admits water into the boiler 14 in the form of a spray much like that produced by a shower head. There seems to be no need for breaking up the incoming water stream into small individual droplets, i.e. atomize same, as the shower head-type spray provides ample surface area to be more or less instantaneously vaporized by the heat developed in the boiler through the burning pyrotechnic device. Of course, smaller holes or tapered holes could be used in perforated plate 74 if they proved to be necessary to accomplish a more complete break-up of the spray individual droplets. Note that the volume of water entering the boiler through bypass conduit 18 and chamber 68 is considerably less than that which enters the boiler through the hollow handle with valve 20 wide open. Thus, when water enters the boiler the handle, there is generally insufficient heat available to bring it to a boil before leaving the boiler due to the greatly increased flow rate. Accordingly, this flow pattern is used for hot water rather than steam. Conversely, by restricting the flow to that which will pass through bypass 18, ample heat is available in the boiler to convert the water to steam.

The cartridge-holder 24 is formed in two parts, namely, an open-ended solid-walled tubular portion 80 that fits loosely inside tube 54 as aforesaid and is generally coextensive therewith, and a perforated tubular portion 82 that threads into the rear end of tube 80 and projects rearwardly therefrom slightly beyond the rear wall 72 of chamber 68. The externally-threaded section 84 on the extreme front end of perforated element 82 screws into the read end of solid-walled tube 80 and provides an abutment against which the rear end of the pyrotechnic cartridge seats. Immediately behind threaded section 84 is a second externally-threaded annulus 86 of greater outside diameter that screws into the internally-threaded portion of tube extension 66. Annular shoulder 88 between the threaded sections 84 and 86 abuts the rear extremity of tube 80.

Extending rearwardly from annulus 86 is an integrally-formed cup-shaped cap portion 90 whose cylindrical sidewall and endwall are both perforated with exhaust apertures 92. This cup-shaped portion lies spaced inward radially from tube extension 66 so as to leave an annular gap 94 therebetween for the escape of the gaseous products of combustion that flow rearwardly. A pair of diametrically opposed ears 96 on the extreme rear end of the cup-shaped portion 90 provide a fingerhold for screwing and unscrewing the cartridge-holding subassembly.

Now, in order to insert a cartridge, element 90 and 80 of the cartridge-holder 24 are unscrewed and removed from tubular extension 66 as a unit; whereupon, the cartridge is dropped into the open front end of the tube 80, ignited, and then the cartridge-holder is reassembled with the cartridge already burning. The front end of tube 80 is screwed tightly against gasket 62 so as to keep the water from contacting the burning pyrotechnic device. Since the front end of the pyrotechnic cartridge is burning, substantially all of the gaseous product of combustion will be exhausted forwardly through tube 58. Next, water is introduced into the boiler either through the hollow handle 16 or bypass conduit 18 and chamber 68. The heated water or steam, as the case may be, exits under pressure from the front of the boiler 14 through neck 32 and into nozzle 26 where it mixes with the gaseous products of combustion that impart additional energy thereto as they leave tube 58.

Nozzle 26 is most clearly revealed in FIGURE 4 and will be seen to include an internally-threaded ring 98 adapted to screw onto the neck 32 of boiler 14, a tubular portion 100 of reduced inside diameter extending forwardly from neck 32 substantially coextensive with tube 58 in spaced coaxial relation outside thereof, a short forwardly-tapered section 102 on the front end of tubular portion 100, and an elongate outlet tube 104 with a slightly curved tapered tip 106 of further reduced cross

section connected to the small end of the tapered section 102. By discharging the gaseous products of combustion well forwardly in the nozzle subassembly, namely, just ahead of tapered section 102, they are picked up and intermixed with the hot water or steam passing forwardly in annular space 108 so as to effectively eliminate any evolution of smoke, noxious or toxic gases at the nozzle tip. More important, however, is the fact that the products of combustion leave the end of tube 58 with considerable velocity and, when they join the stream of water or steam, a substantial amount of additional kinetic energy is imparted to the latter which materially facilitates the cleaning operation. Of course, any one of a number of different types of spray tips, both long and short, could be substituted for the one shown without the exercise of invention.

The resulting unit is quite safe to use despite the fact that the temperature of the burning pyrotechnic cartridge can easily exceed 1000° F. With the cartridge-holder 24 open both forwardly and rearwardly, there is almost no possibility of a pressure build-up in the unit of sufficient magnitude to rupture the boiler. It is desirable to leave a small annular space between tubes 54 and 80 to accommodate unequal thermal expansion of the latter that might otherwise cause the cartridge-holder to freeze inside boiler tube 54 until the apparatus cools. As it is, the cartridge burns at the front end, and the rear end of the cartridge-holder remains relatively cool to the touch until the cartridge is almost completely spent; therefore, under most circumstances, the cartridge-holder 24 can be removed from the boiler even with the cartridge still burning. When this is done, merely tipping the front end of the cartridge-holder down will let the cartridge fall out or, preferably, the whole subassembly including the cartridge can be emersed in a bucket of water if the user does not want to wait for the time interval required to extinguish same by letting water in through openings 64.

Finally, a few words about the pyrotechnic cartridge. The unit has been designed to accept a conventional road flare of the type already carried by most commercial vehicles and many passenger cars. These flares are quite inexpensive, generally about five cents apiece or less, and they are widely available at service stations, garages and automotive parts supply houses. These flares usually burn about twenty minutes which is more than adequate for most steam-cleaning jobs. They burn on the average at temperatures in excess of 1000° F. which is sufficient to more or less instantly boil a reasonably large flow of cold tap water, say that which will flow through a 1/4 inch inside diameter tube at ordinary household water pressure of 30 to 40 p.s.i.

The smoke evolved upon burning these flares is, of course, of no value in the steam-cleaning operation other than as a source of kinetic energy and it is undoubtedly possible to design a special pyrotechnic cartridge with reduced smoke evolution while producing only non-toxic gases. Obviously, whenever the cartridge is burning, some water should be flowing through the boiler to keep the temperature of the system down to safe reasonable limits. On the other hand, letting the cartridge burn in the unit with no water in it is no more dangerous than using the same flare by itself, assuming the area is adequately ventilated.

Having thus described the several useful and novel features of the portable steam-cleaning apparatus of the present invention, it will be apparent that the many worthwhile objectives for which it was developed have been achieved. Although but a single specific embodiment of the invention has been illustrated and described in detail herein, I realize that certain changes and modifications may well occur to those skilled in the art within the broad teaching hereof.

What is claimed is:

1. The portable spray-cleaning apparatus which comprises: a liquid and vapor-tight pressure vessel having an

inside wall dividing the interior thereof into a steam compartment and a fuel compartment in heat-exchange relation to one another, said steam compartment including a water inlet connectable to a source of water under pressure and a steam outlet remote from said inlet, said fuel compartment opening onto the exterior of said vessel for the reception of a solid pyrotechnic fuel cartridge, and said fuel compartment cooperating with a fuel cartridge inserted therein to define a combustion chamber remote from said exterior opening adapted to confine the gaseous products of combustion; conduit means connected into the combustion chamber of the fuel compartment adapted to receive the gaseous products of combustion generated therein and deliver same to the steam outlet to be mixed with the steam issuing therefrom; and, nozzle means connected to the pressure vessel at the steam outlet, said nozzle means being adapted to receive the stream of mixed gases and direct same under pressure against a workpiece.

2. The portable spray-cleaning apparatus as set forth in claim 1 in which: a perforated partition wall is located within the steam compartment in position to separate the water inlet from the steam outlet, said partition wall being adapted to obstruct the incoming stream of water and convert same into a spray as it passes therethrough.

3. The portable spray-cleaning apparatus as set forth in claim 1 in which: a handle is attached to the pressure vessel, said handle having a flow-passage therethrough with its inlet end connectable to the source of water under pressure and its outlet end communicating the interior of the steam compartment through the water inlet.

4. The portable spray-cleaning apparatus as set forth in claim 1 in which: the inside wall of the pressure vessel is substantially tubular and provided with at least one aperture adjacent the end thereof remote from the exterior opening; and, in which a tubular cartridge-holder adapted to accept a cylindrical fuel cartridge is telescoped into said tubular wall of the pressure vessel, said cartridge-holder being movable relative to said tubular vessel wall between a closed position covering the aperture in the latter and an open position uncovering same so that water may enter the combustion chamber and extinguish a burning fuel cartridge therein.

5. The portable spray-cleaning apparatus as set forth in claim 1 in which: the pressure vessel is generally cylindrical in shape with both front and rear endwalls, the front endwall containing the steam outlet, the inside wall being tubular and opening through the rear endwall while terminating short of said front endwall; and, in which the conduit means comprises a smaller diameter tube extending forwardly through the steam outlet from the combustion chamber in the front of the fuel compartment.

6. The portable spray-cleaning apparatus as set forth in claim 3 in which: the pressure vessel includes a second water inlet opening into the steam compartment and a perforated partition wall within the latter compartment separating said second inlet from the first inlet and the steam outlet, said second inlet being connectable to a source of water under pressure, and said partition wall being adapted to receive a stream of water entering through the second inlet and convert same into a spray

as it passes therethrough; and, in which a flow-control valve is connected into the flow-passage in the handle.

7. The portable spray-cleaning apparatus as set forth in claim 4 in which: a plate with an opening therein covers the front end of the tubular vessel wall at right angles to the axis thereof; the conduit means connects into the combustion chamber through the opening in said plate; and, in which the front end of the cartridge-holder is open and lies in a plane normal to the longitudinal axis thereof, said end being adapted to form an essentially liquid-tight seal with the adjacent face of said plate when in abutting relation thereto.

8. The portable spray-cleaning apparatus as set forth in claim 4 in which: a portion of the cartridge-holder is accessible through the exterior opening in the fuel compartment of the pressure vessel, and said accessible portion contains at least one exhaust opening adapted to prevent the build-up of excessive gas pressure within said cartridge-holder.

9. The portable spray-cleaning apparatus as set forth in claim 5 in which: a perforated partition wall within the steam compartment separates the water inlet from the steam outlet, said partition wall being adapted to convert a stream of water entering the water inlet into a spray as it passes therethrough.

10. The portable spray-cleaning apparatus as set forth in claim 5 in which: a plate with an opening therethrough covers the front end of the inside tubular vessel wall in perpendicular relation to the longitudinal axis thereof; the conduit means connects into the combustion chamber through the opening in the plate; the inside tubular vessel wall has at least one opening therethrough adjacent the front end thereof; and, in which a tubular cartridge-holder is telescoped into the inside tubular vessel wall, the cartridge-holder having an open front end adapted to abut the inside of the plate and form an essentially liquid-tight seal therewith isolating the interior of said cartridge-holder from the contents of the steam compartment.

11. The portable spray-cleaning apparatus as set forth in claim 7 in which: a high temperature gasket is placed on the inside surface of the plate in position to seal against the open end of the cartridge-holder when the latter is placed thereagainst.

12. The portable spray-cleaning apparatus as set forth in claim 8 in which: the cartridge-holder is threaded into the tubular vessel wall, the projecting end of said holder comprises an apertured cap, and means are carried by said cap in position to form fingerholds adapted to facilitate insertion and removal of said holder.
